TABLE LEG

Robert E. Kjer Jakobsen, Manhattan Beach, Calif., assignor to Virtue Bros. Mfg. Co., Los Angeles, Calif., a corporation of California

Application January 19, 1959, Serial No. 54,238

Term of patent 14 years

(Cl. D33—14)

Fig. 1 is a broken perspective view of a table leg showing my new design.

Fig. 2 is a top plan view thereof.

Fig. 3 is an enlarged cross-sectional view as taken on the line 3—3 of Fig. 1.

I claim:

The ornamental design for a table leg, substantially as shown.
